[57] CLAIM

The ornamental design for a spool configured storage barrel, as shown and described.

DESCRIPTION

FIG. 1 is a perspective view of a spool configured storage barrel showing our new design;

FIG. 2 is a perspective view of a second embodiment of the design of FIG. 1;

FIG. 3 is a top plan view of the design of FIG. 1;

FIG. 4 is a top plan view of the design of FIG. 2;

FIG. 5 is a front elevational view of the design of FIG. 1, the same view of the second embodiment being identical;

FIG. 6 is a side elevational view thereof, the opposite side being a mirror image; and,

FIG. 7 is a back elevational view of the design of FIG. 1, the same view of the second embodiment being identical.

The design is of a decorative storage barrel having a general configuration of an enlarged spool, the exterior of which is over-layered with a material or graphic illustration of a material having a thread-like appearance, the order of the "threads" of which may vary.

The broken line showing of articles inside the barrel, in FIG. 1, is for illustrative purposes only and forms no part of the claimed design.
